UNITED STATES PATENT OFFICE

PATRICK F. DENNING, OF CLEVELAND, OHIO

ELECTRIC CIRCUIT CONTROLLER

Application filed April 18, 1930. Serial No. 445,510.

This invention relates to circuit controllers which are used principally on automobiles for controlling the operation of a stop light or other similar signal lights. More particularly, it pertains to improvements in a device on which Letters Patent of the United States, No. 1,729,929, were granted to me October 1st, 1929.

The objects of the present invention are the provision of improvements in the aforesaid controller, that will add materially to the life of the device and facilitate the assembly and operation thereof.

Referring now to the drawings, Fig. 1 is a longitudinal section through part of a motor vehicle embodying my invention; Fig. 2 is a side elevation of the switch on a larger scale than in Fig. 1; Fig. 3 is a vertical section taken on line 3-3 in Fig. 2; Fig. 4 is a section taken on the line 4-4 in Fig. 2; Fig. 5 is an enlarged sectional view through one of the contact members; Fig. 6 is an exploded perspective view of the major parts of the switch; Fig. 7 is a section taken through the movable contact member, and Figs. 8 and 9 are perspective views showing different steps in the method of manufacture of the switch shaft.

Referring in detail to the drawings, A represents the main sub-frame of an automobile, and B a short section of the floor boards. C is a rear axle, one of the drive wheels being shown at D. The switch comprising my invention is indicated generally at 1 and may be attached to the floor boards, as shown. The switch may have electrical conductors such as the usual insulated wires 2 and 3, the former leading to a battery E shown diagrammatically in Fig. 1, and as being grounded to the frame at F. The conductor 3 may lead to a signal light G at the rear of the car, one terminal of the signal being grounded to the frame as at H. The switch may be controlled from the brake pedal indicated at J, which is connected at its lower end to a brake con-

trolling rod M. The rod has a switch controlling part N in the nature of a bracket, which is suitably clamped onto the control rod so that it reciprocates with it when the brakes are operated to stop the car.

The primary controlling elements of the switch comprise stationary contacts 5 and 6 and a movable bridging contact member 7. The contact 5 is electrically connected to the conductor 2 and the contact 6 similarly connected to the conductor 3.

The movable conductor is arranged to move into and out of engagement with one of the stationary contacts, when the switch is respectively operated to the "on" and "off" positions. Heretofore, the edge of the movable contact member which engages the stationary contact members has been turned downwardly and fastened into the block of insulating material on which the movable contact member is mounted. Furthermore, a relatively large helical compression spring has been used for urging the movable member axially and toward the stationary contact members. Such spring was also used to aid in the return of the movable contact member when the pressure on the foot pedal was released. The effect of such spring tension has been to wear a groove in the block of insulating material on which the movable member was mounted, thus causing a shoulder on the movable member to be presented to the stationary member at the time of contact. As a result, the movable member quickly became worn through.

I have overcome the tendency of the movable member to wear in such manner by fastening it to the block 15 of electrical insulating material, only at one end 16 and at an intermediate point 17. The other end 18 is free to move toward and away from the block, and as shown at 19 in Fig. 7, is bent toward the block. An aperture 21 in the block provides an opening into which the end 19 may be moved at the moment of, and

during contact. Normally, the spring tension of the metal, of which the movable contact member is made, keeps it slightly away from the face of the block, as is shown in Fig. 7.

With this arrangement, the inwardly turned portion of the movable contact member provides a ramp or inclined surface which prevents the formation of a shoulder, notwithstanding the fact that a groove may be worn in the block of insulating material.

To assist further in the elimination of wear on the block, and on the movable member, I make the contact screws 20 hollow and fill them with grease or other plastic lubricating medium, with the result that as the ends of the screws become worn, additional lubricating material is available for use.

I provide additional means for minimizing the wear between the movable and stationary contacts by utilizing a relatively large helical compression spring 25, one end of which is fastened as at 26, to a retaining plate 27, and the other end of which is provided with a hook 28 for engagement with a post 29. This relatively large spring is thus mounted as a unit upon the retaining plate and can easily be positioned on the shaft 30. In addition, the retaining plate has an ear 31 which limits rotative movement of the plate in one direction, and another ear 32 which limits such movement in the opposite direction. The function of the relatively large spring, therefore, is merely to assist in returning the shaft to the normal position when pressure is released on the foot pedal.

To urge the movable contact plate into engagement with the stationary contact members, I use a relatively small helical spring 33, which as shown in Figs. 3 and 4, is disposed between the plate 27 and the block 15, and as surrounding the shaft 30. By using a relatively small spring for this purpose, I reduce further the pressure and therefore, the degree of wear between the relatively movable and stationary contact members.

The switch shaft is journaled in the parts 34 and 35 which co-operate to provide the casing. Such shaft projects at one end beyond the part 34 and is squared as at 40 to receive a bar 41 which in turn is connected to the member "N" by a link 42. The shaft 55 is shown as having a flat portion 41 between the casing parts while the plate 27 and insulating disc 15 are shown as having complementary-shaped apertures through which the flat portion of the shaft extends.

To make the shaft cheaply and quickly, a strip of bar stock is blanked, as is shown at 45 in Fig. 8 and is then passed between the dies which form the cylindrical parts 46 and 47, as is shown in Fig. 10. This method of manufacture obviates the necessity for ma-

chining the shaft and provides a simple and practical method of manufacture.

By means of the improvements which I have described and illustrated, I have been able to increase about three fold the life of the switch. Furthermore, I have utilized features which facilitate the manufacture and simplify the assembly thereof.

I claim:

1. An electric circuit controller comprising a hollow housing, a pair of stationary contacts mounted in said housing, a shaft having its respective ends supported by said housing, means disposed outside the housing to rotate the shaft, a block of insulating material splined on the shaft, a contact plate carried thereby, and adapted to engage one of the stationary contact members continuously and to engage the other contact member selectively, said plate having at least one end thereof inclined toward said block and freely movable with relation thereto, and being attached to the block at an intermediate point whereby additional contacting surface is presented as the block becomes worn during use.

2. An electric circuit controller comprising in combination, a hollow housing, a pair of relatively stationary electrical contacts carried thereby, a relatively movable contact member positioned within the housing and coacting with the stationary contact members, said movable member comprising a sheet metal plate, means for attaching the plate to the disc at a point intermediate the ends of the plate, there being a disc of insulating material supporting the plate, said disc having an opening therein, and said plate having one end thereof extending into the opening and being freely movable toward and away from the disc whereby through the formation of additional metal a shoulder on the plate is prevented as the block becomes worn during use.

3. An electric circuit controller comprising a hollow housing, relatively stationary contact members carried thereby and projecting into the housing, and a relatively movable flexible member mounted within the housing at least one of the stationary contact members comprising a threaded member having a hollow recess, there being plastic lubricating material disposed within the recess, the recess being open adjacent the contacting surface whereby the contact members are progressively lubricated as they become worn during use.

4. An electric circuit controller comprising a hollow housing, relatively stationary contact members carried by the walls of the housing and projecting into the interior thereof, a relatively movable flexible contact member positioned within the housing and coacting with the stationary contact members, a block of insulating material support-

ing the relatively movable member and having an opening into which one end of the relatively movable member extends, at least one of the relatively stationary contact members having a hollow interior adapted to receive and hold lubricating material, and being open on the contacting end thereof whereby lubrication between the contact members is affected as they become progressively worn during use.

10 In testimony whereof, I hereunto affix my signature.

PATRICK F. DENNING.
